Application April 13, 1949, Serial No. 87,186

9 Claims. (Cl. 15—192)

1

This invention relates to a brush and the method of making it. The invention relates particularly to the setting of synthetic bristles within a ferrule so that the butts of the bristles, the ferrule and the cementing composition become integral in the curing of the cementing composition, and do not shrink away from each other as the cured product cools.

The application is a continuation in part of our copending application Serial No. 75,856 filed February 11, 1949 for Bristle Setting, now abandoned.

Although synthetic bristles of nylon, cellulose acetate, and the like have been known for several years and there has been a shortage of the China bristles, there has not been developed as yet any entirely satisfactory and universally used method of setting such synthetic bristles within a ferrule. Phenol aldehyde condensation products have been used but the setting with them is at best difficult to control. With other cementing compositions there have been many instances of separation of the assembled and cemented bristles from the surrounding ferrule, due to the fact that the coefficient of expansion on heating or shrinkage on cooling is at least several times as large for the synthetic bristles as for the metal of the common ferrule.

In using nylon bristles, for instance, we have endeavored in early experiments to correct for the shrinkage of the cemented bristle butts away from the ferrule on cooling subsequent to curing the cement. We have coated the bristle butts within a metal ferrule with the cementing composition and cured in usual manner; after the curing and cooling, we have replaced the ferrule by a smaller one which fits tightly around the now shrunken cemented bristles. This expedient is obviously inconvenient and has proven unsatisfactory.

The present invention relates to a bristle setting in which the whole assembly, including the bristle butts themselves, the surrounding ferrule and the cementing composition become integral and in which there is no separation of the cemented bristles from the ferrule as the product is cooled subsequent to the heating step to harden the cementing composition and in which a resilient ferrule, in one embodiment of the invention, extends in stretched condition tightly around the assembled and cemented bristle butts.

Briefly stated, the invention comprises a brush in which the ferrule and the synthetic bristles used are soluble in a common solvent and in which the bristles are united integrally together and also to the inside of the ferrule by treatment with such common solvent. In one embodiment the invention comprises such brush in which the ferrule is constructed of plastic material having the same or a higher tempera-

2

ture coefficient of expansion (and therefore of shrinkage on cooling) than the material of the bristle butts so that, as the assembly is cooled after the heating step, the ferrule shrinks at least as much in proportion as the bristles themselves and adheres tightly around the exterior of the bristle assembly. In the preferred embodiment, the invention comprises also the use of the cementing solvent in limited proportion; the proportion must be adequate only to wet the exterior surfaces of all of the bristle butts and the portion of the ferrule surrounding the bristle butts, but inadequate to convert them by solvent action to a flowable mass. In such proportion the solvent becomes a part of the solid material and remains fixed either in the form of a new chemical compound or as a solid solution in the finished cemented assembly of the bristles within the ferrule.

The invention comprises also the herein described method of making a brush of the kind described.

The invention will be further illustrated by description in connection with the attached drawing to which reference is made.

Fig. 1 is a plan view of the improved brush, partly broken away for clearness of illustration.

Fig. 2 is a sectional view on line 2—2 of Fig. 1.

Fig. 3 is a sectional view on line 3—3 of Fig. 1.

There are shown ferrule 10, bristles 12 in an assembly packed at the butt ends within the ferrule, and spacer strips 14 extending in spaced relationship to each other through the bristle assembly so as to space the bristles at their butt ends into layers. The bristle butts are adhered in the zone 15. There are shown also the cap 16 extending over the tips of the bristles in the final assembly and conventional handle 18.

The thickness of the cap is exaggerated for the purpose of illustration. The solvent for the bristle butts and ferrule referred to later herein is not shown in the drawing for the reason that the solvent is not visible in the finished assembly.

The bristles used in our invention may be the commercial synthetic filaments which are sold as a substitute for hog bristles as, for instance, tapered nylon, cellulose acetate, cellulose acetate butyrate, methyl methacrylate, polyvinyl or polyvinylidene chloride filaments. It will be understood that the synthetic bristle selected should be one which is suitable for the use to which the brush is to be put. For a paint brush, for instance, the filament selected should be one that is not soluble in the paint oils. For a lacquer the filament should be insoluble in the common lacquer solvents. The nylon and the various plastic vinyl compounds in bristle form have the widest applicability because of resistance to a wide variety of solvents.

The ferrule is constructed of any one of the

plastic materials given as satisfactory for the bristles. There is advantage in having the same plastic selected for both the ferrule and the bristles. If another plastic is selected for the two parts of the brush, then there should be a certain relation between the temperature coefficient of expansion of the material of the ferrule and that of the synthetic bristles; the ferrule should shrink at least as much as the bristle assembly when the whole is cooled from the temperature of curing of the cement. Some leeway is allowable in the relative coefficients of expansion when the assembly is made according to our method; in this method the ferrule is ordinarily heated to a considerably higher temperature than the inside of the assembly during the fabrication process. The ferrule in cooling through the wider range of temperature from that to which it is initially heated down to room temperature should undergo at least the same total shrinkage as the inside of the assembly experiences in cooling through a more limited range of temperature. When a resilient ferrule such as one of nylon is used around a nylon interior, the greater range of cooling of the ferrule may cause the ferrule to be in stretched condition in the cooled assembly. For universal conditions of effecting the cementing at elevated temperatures, as when the heating is continued so long that the whole assembly becomes the same in temperatures throughout, the ferrule should be constructed of material having a coefficient of expansion at least as large as the coefficient for the bristles.

The solvent used to effect the adherence of the bristles to each other and to the inside of the ferrule must be a common solvent for the material of the bristle butts and the material of the ferrule. The solvent is one which in the proportion used should thicken as the material of the bristle butts and ferrule dissolve in the solvent to the extent of giving solvent softened surfaces. Such high boiling solvents as the cresols or like phenolic solvents are preferred. Examples of these that are satisfactory are meta- or para-cresol, meta tertiary butyl cresol, orthophenyl phenol, and any one of the isomeric xylenols. These phenolic solvents may be used alone or mixed with one another. There may be used other high boiling solvents selected in accordance with the known solubilities of the particular material present in the bristle butts and the ferrule. When the bristle butts and the ferrule are polymerized methyl methacrylate (Lucite), for instance, then the reactive solvent used may be methyl methacrylate monomer.

Another solvent that may be used is a high boiling fatty acid or anhydride, examples of which are sebatic acid and adipic acid.

These solvents are substantially non-reactive chemically with the material of the bristles and ferrule and form therewith solutions that are flowable at elevated temperatures and hard when cooled.

The spacer strips 1/4 also should be selected to have solubility in common with the bristle butts and the inside of the ferrule, in fact they are preferably constructed of the same material so that any solvent for the synthetic bristles and the ferrule would be also solvents for the separator strips and the whole structure would be integrally united in the finished brush.

The solvent should be used in limited proportion adequate to wet all of the surfaces that are to be adhered, including adjacent surfaces of

the bristle butts, separator strips, and inside of the ferrule but not sufficient to convert any of these parts of the brush to flowable condition. We have used to advantage about 1.5 to 3.5 cc. of the solvent for application over the butt ends of the bristles having an area of surface of 3 sq. inches, this being in a brush with ferrule about 4 inches wide.

In a modification of the invention we introduce plastic material dissolved in the solvent, the plastic being one of the kinds listed above and preferably the same kind as used in the construction of the bristles. This dissolved material is useful when the solvent is of low viscosity as applied and does not interact quickly with the bristles to form a solid mass so as to prevent excessive penetration of the solvent beyond the place of application of it.

The solvent is suitably applied over the tips of the uncoated bristle butts as by being brushed thereover or sprayed thereover. We prefer spraying as the most certain means of obtaining distribution of the solvent over the entire exposed area of the bristle butts assembled in the ferrule and over the inside of the ferrule at the level of these bristle butts.

When the solvent has been applied over the tips of the bristle butts, then the cap is poured, as by flowing the solvent or solvent solution of the plastic material over the bristle butts. Thus, the solution of the same plastic as contained in the bristle butts and the same solvent as applied thereto is flowed over the tip ends of the bristle butts in amount about the same in volume or somewhat greater than the volume of solvent previously applied, the solvent having been allowed to penetrate somewhat between the bristles.

During the application of the solvent and of the cap, the bristle assembly is maintained in upright position with the butt ends up.

This position is maintained while the thus treated assembly of the bristles within the ferrule is sent through a heating oven. Here heat is applied for a short time only as this is all that is required to cause conversion of the solvent and cap to hard solid form. Thus we may heat at temperatures 150-325° F. Exposure is short and the time of exposure varies, with the exposure being shorter within the range stated at high temperatures and the exposure longer at low temperatures. Thus the exposure is of the order of 30 minutes at 150° F., 15 minutes at 190° F., and 3 or 4 minutes at 325° F. We prefer to use 275° F. for a period of 5 to 7 minutes. These short periods are all that are required to cause conversion of the originally fluid and somewhat volatile solvent to solid form that remains within the material of the bristle butts and inside the ferrule. In some instances the period of time to cure the cap must be extended above the illustrative times shown, as, for instance by 5 minutes at a given temperature. The hard form appears after cooling.

In this short heating the outside of the assembly comes to have a substantially higher temperature than the interior. Because the temperature coefficient of the plastics is many times that of the sheet steel which composes most of the common metal ferrules, the shrinkage effects are pronounced. With the selection of ferrule and bristle material as described we obtain either no shrinkage of the central part of the assembly from the ferrule or an actual increasing of the tightness of the ferrule due to its greater shrinkage as it cools over the wider range as

compared to the range of cooling of the solid coated bristle butts. The ferrule stretches if necessary to accommodate itself to the dimensions of the interior of the assembly.

The invention will be further illustrated by detailed description in connection with the following specific example of the practice of it.

Example

The nylon bristle pack is inserted in the nylon ferrule. The pack is then sized out to the depth of adhesion required, as for instance $\frac{3}{8}$ inch. A mixture of m-paracresol is then sprayed over the surface of the butt ends and inside the ferrule. The amount of this cresol sprayed is 1.8 g. for the bristle assembly for a 4 inch paint brush. Following the application of the cresol mixture, the capping is applied. This consists of a solution of nylon in m-paracresol. Application may be made either by pouring or spraying. The quantity used is approximately 1.5 to 3.5 cc. for a brush of the kind described. All applications are made with the bristle butts in an upright position.

Following the capping procedure the brush is placed in an oven at an air temperature of 275° F. for a period of 7 minutes. At the end of this time the brush is removed and cooled. Prior to cooling care must be taken not to bend or in any way damage the warm nylon bristles.

Brushes made as described show no separation of the ferrule from the bristles or separation of the bristles from each other or from the spacer strips.

Special advantages are found in our product. It is not necessary to insert fasteners through the ferrule and bristle assembly. It is unnecessary to have a wide zone of cementing. In conventional brushes, it would be necessary to make certain that the bristles are united at a level below that of later insertion of the fasteners either by drilling or driving or both; otherwise there would be loosening of bristles below the point of adhesion so that they would fall from the brush. In our new product it is not necessary to extend the zone of union of the bristles to any particular level so long as they are firmly united at their butt ends. The brushes are durable in use and their manufacture is certain and dependable.

It will be understood that it is intended to cover all changes and modifications of the example of the invention herein chosen for the purpose of illustration which do not constitute departures from the spirit and scope of the invention.

What we claim is:

1. In setting synthetic bristles tightly within a ferrule, the method which comprises assembling thermoplastic bristle butts in uncoated condition within a thermoplastic ferrule having a temperature coefficient of shrinkage at least equal to that of the plastic of the bristle butts, applying over the assembled butts a flowable solvent for the bristle butts and for the ferrule, the solvent being substantially non-reactive chemically with the plastic bristles and ferrule, forming therewith solutions that are flowable at elevated temperatures and hard when cooled, and being added in quantity adequate to wet all the bristle butts and the inner surface of the surrounding portion of the ferrule but less than sufficient to dissolve completely either one thereof, then warming the solvent treated assembly to the temperature of softening of the exteriors of the butts and ferrule by the solvent, and then cooling the resulting product to room temperature, so that the

softened material hardens and the ferrule and bristles are united in an integral structure.

2. The method described in claim 1, including warming the ferrule to a temperature substantially above that of the bristle butts so that, in the said cooling, the ferrule cools through a greater range of temperature and, in the cooled product, is in stretched tight condition around the bristle butts.

10 3. In setting synthetic bristles with a ferrule, the method which comprises assembling nylon bristle butts in uncoated condition within a nylon ferrule, applying over the assembled butts a liquid solvent for the bristle butts and the ferrule, 15 the solvent being added in quantity adequate to wet all the bristle butts and the inner surface of the surrounding portion of the ferrule but less than sufficient to dissolve completely the bristle butts or the ferrule, then warming the 20 solvent treated assembly so that some material of the bristle butts and ferrule is softened by the solvent, and then cooling the resulting product to room temperature, so that the bristle butts and ferrule are united in an integral structure.

25 4. The method described in claim 3, the phenolic solvent being a cresol.

5. The method described in claim 3, the said solvent being a phenolic solvent and the temperature of said warming being about 150° to 325° F.

30 6. The method described in claim 1, including applying a thin layer of solution of the material of the bristle butts in the said solvent as a cap over the solvent-treated bristle butts before the said warming and then effecting the warming and subsequent cooling, so that the cap, bristles, and ferrule become integrally united.

35 7. The method described in claim 1, the ferrule being warmed to a substantially higher temperature than the interior of the bristle assembly so that the ferrule shrinks over wider range of temperature on cooling than does the bristle assembly, the ferrule and the bristles being composed of the same plastic material.

40 8. A brush comprising a handle, a thermoplastic ferrule, thermoplastic bristles packed at their butt ends tightly within the ferrule and material which is a solvent for the bristles and ferrule when heated and a solid at ordinary temperatures extending as a cement between the bristle butts and the inner surface of the surrounding portion of the ferrule and bonding the bristle butts and ferrule in an integral structure.

45 9. A brush comprising a handle, a nylon ferrule, nylon bristles packed at their butt ends tightly within the ferrule, and nylon cement adhering the bristles at their butt ends to each other and to the inner surface of the surrounding portion of the ferrule, so that the whole is an integral structure.
